REMOTE CONTROL DEVICE

Philip L. S. Lum, Chatham, N. J., assignor to
 L. A. B. Corporation, Newark, N. J., a corpora-
 tion of New Jersey

Application August 26, 1933, Serial No. 686,896

16 Claims. (Cl. 250—20)

This invention relates generally to remote control devices and the invention has reference, more particularly to a novel remote control device adapted for controlling the operation of a plurality of independently operable elements as, for example, the tuning and volume control elements of a radio receiving set.

Remote control devices heretofore employed for operating radio receiving sets from a distance have generally been unsatisfactory in use for various reasons. Some of these devices merely serve to control the tuning dial of the radio set, thereby making it necessary for the user to go to the radio set itself to start the set and to control the volume thereof. Others of these devices serve to operate both the volume and tuning controls from a distance, but fail to indicate to the user the position of the tuning dial so that it is difficult to tune. Also, many of these devices tend to overrun resulting in hunting, thereby making it very difficult to properly tune in stations. Most of these devices are quite complicated and are easily deranged, thereby rendering the same costly and undesirable in use.

One object of the present invention is to provide a novel remote control device arranged to be readily installed in connection with radio receiving sets and adapted to enable complete operation of the set from the remote point of control, such remote control operation including tuning and volume control of the set as well as starting and stopping, the said device being exceedingly reliable in use and easily operated.

Another object of the present invention lies in the provision of a novel remote control device that enables the radio set to be controlled in all its operations by the use of but a single knob, the said device being designed so that the set can be controlled either by a single knob on the set or by a single knob at any desired remote point, the remote control in no way interfering with the local control of the set.

Another object of the present invention is to provide a novel remote control device of the above character having tuning indicating means or dial at the remote point of control which tuning indicating means may be readily synchronized and maintained in synchronism with the tuning indicating means or dial of the set itself, whereby the operator at the remote point of control may readily tune in a station when he knows the number thereof on the set tuning dial.

Still another object of the present invention lies in the provision of a novel remote control device that employs differential gearing for se-

lectively operating the tuning and volume control of the set either by hand or by motor driven means, the said device being extremely compact and cheap to manufacture and being substantially fool proof in use.

A further object of the present invention is to provide a remote control device of the above character that employs reversible motor means for turning either the radio volume control shaft or the radio tuning control shaft, the operation of the volume control shaft in no way interfering with the position of the tuning indicating means either of the radio set or of the remote control unit.

Other objects of this invention, not at this time more particularly enumerated, will be clearly understood from the following detailed description of the same.

The invention is clearly illustrated in the accompanying drawings, in which:

Fig. 1 is a view in side elevation with parts broken away illustrating the novel remote control device of this invention applied to a radio receiving set.

Fig. 2 is a vertical sectional view with parts broken away taken substantially along line 2—2 in Fig. 1, but illustrates the remote control unit in plan.

Fig. 3 is an enlarged sectional view taken substantially along the line 3—3 of Fig. 1.

Fig. 4 is a sectional view taken substantially along the line 4—4 of Fig. 3.

Fig. 5 is a sectional view taken substantially along the line 5—5 of Fig. 4.

Fig. 6 is a schematic view illustrating the operation of the device.

Fig. 7 is a wiring diagram illustrating the electrical circuits involved.

Fig. 8 illustrates a modified form of wiring diagram.

Fig. 9 is a schematic view illustrating the control device of this invention employed for operating three independently operable elements, and

Fig. 10 is a sectional view taken substantially along line 10—10 of Fig. 9.

Similar characters of reference are employed in said views, to indicate corresponding parts.

Referring now to Figs. 1 to 7 of the drawings illustrating an embodiment of the invention, the reference numeral 1 designates the front panel of a radio set having a volume control unit 2 provided with a starting switch 3 incorporated therein in a manner well known to those skilled in the art. The radio set is provided with a tuning dial 55

4 (see Fig. 2) fixed on the condenser shaft 5 in the usual manner.

According to the preferred arrangement, a reversible motor 6 is contained within the radio set cabinet, the said motor being preferably of the squirrel-cage, shaded pole induction type, the said motor having a stator winding 7, a rotor 8 mounted on rotor shaft 11, and shading coils 9, 9' and 10, 10'. Motor 6 is shown mounted on a suitable frame 12. A pinion 14 is fixed upon the rotor shaft 11 and meshes with a gear 15 that is fixed upon a worm shaft 16 which is journaled in bearings provided in the frame 12. Worm shaft 16 has a worm 17 thereon which meshes with a worm gear 18 that is secured upon the hub of a bevel gear 19 that constitutes one gear of a differential gear set having an opposing similar bevel gear 20 provided with a hollow hub 21 that is journaled in a bearing provided in the frame 12. The differential gear set has an arm 22 intermediate the two bevel gears 19 and 20, which arm carries beveled pinions 23 that mesh with gears 19 and 20.

Hollow hub 21 of bevel gear 20 has a coupling yoke member 24 fixed thereon. Yoke member 24 is shown as having two driving pins 25 which project loosely through apertures provided in a coupling disc 26, which coupling disc is fixed as by a pin 27 to a shaft 28 that has its inner end portion journaled in the hollow interior of hub 21 and its outer portion journaled in a bearing block 29 carried by the front panel 1. A coil compression spring 30 is interposed between the coupling disc 26 and the bearing block 29 and serves to normally press the coupling disc 26 toward the coupling yoke 24, thereby urging shaft 28 rearwardly with respect to the front panel 1. The forward end of shaft 28 projects through bearing block 29 and has a control knob 31 fixed thereon in front of panel 1.

The arm 22 of the differential gear set is secured as by a pin 32 upon a shaft 33 that is aligned with the shaft 28. The bevel gear 19, carrying the worm wheel 18, is rotatably supported upon the shaft 33. Shaft 33 has its forward end portion journaled in the hollow interior of hub 21 and has its rear portion journaled in the hollow interior of the hub 34 of a bevel gear 35 constituting a member of a second differential gear set. The second differential gear set has a bevel gear 36 arranged in opposition to the bevel gear 35, the said bevel gear 36 being turnably mounted upon the shaft 33. The second differential gear set has an arm 37 that is secured as by pin 38' to the shaft 33. Arm 37 carries pinions 38 that mesh with the bevel gears 35 and 36. The hollow hub 34 of bevel gear 35 of the second differential set is journaled in a bearing provided in the frame 12 and the rear portion of this hub 60 has a pinion 55 fixed thereon which pinion meshes with a gear 56 that is keyed upon the shaft 57 of the volume control unit 2.

Bevel gear 36 has a ratchet wheel 39 secured thereto, which ratchet wheel has a pulley 40 provided thereon, the said pulley being adapted to drive a transmission cable or belt 41. Cable 41 passes over sheaves 42 (see Fig. 2) and around the tuning dial 4 for turning this dial. Bevel gear 35 has a ratchet wheel 43 secured thereto which ratchet wheel is similar to the ratchet wheel 39. Ratchet wheels 39 and 43 are adapted to be selectively engaged by a double acting pawl 44 that is pivoted upon a transverse supporting shaft 45 which shaft is carried by pedestal 46. Pawl 44 is provided with an arm 47 that serves as an

armature for an electro-magnet 48, the said electro-magnet having a coil 49.

A coiled tension spring 50 has one end thereof attached to the arm 47 and the other end thereof attached to the frame 12 and serves to normally urge the pawl 44 in a clockwise direction about the shaft 45 as viewed in Fig. 1, thereby tending to cause this pawl to engage the ratchet wheel 43 in stopped relation. The spring 50 opposes the electro-magnet 48, but when this electro-magnet 10 is energized, the same by acting upon arm 47 serves to turn the pawl 44 in a counterclockwise direction about shaft 45 against the tension of spring 50, thereby causing this pawl to engage ratchet wheel 39 in stopped relation. 15

A link 51 has its rear end pivotally connected as by a screw 52 to the arm 47 and the forward portion of this link extends slidably through an apertured supporting bracket 53. The forward end of the link 51 is bent upwardly at 54 so as to engage the front surface of the coupling disc 26. By pulling outwardly upon the knob 31, the coupling disc 26 is moved forwardly compressing spring 30 somewhat and moving the link 51 forwardly, thereby turning pawl 44 in a counterclockwise direction as viewed in Fig. 1 and causing this pawl to engage ratchet wheel 39 in stopped relation. 20

Thus, if it is desired to operate the radio set by local control as when the operator is standing at the set itself, use is made of the local control knob 31. To start the set, the operator merely pulls this knob 31 forwardly somewhat, causing pawl 44 to engage ratchet wheel 39, whereupon the turning of knob 31 will cause coupling 26—24 35 to revolve bevel gear 20 of the first named differential gear set. Since bevel gear 19 is held stationary by worm wheel 18 and worm 17, the turning of gear 20 will cause arm 22 to turn in the same direction as gear 20 but at half the speed of this gear 20. The turning of arm 22 causes shaft 33 to turn and since bevel gear 36 of the second differential gear set is held stationary, the arm 37 will rotate causing bevel gear 35 to rotate in the same direction as the arm 37 but at twice its speed, i. e. at the speed of knob 31. Bevel gear 35 rotates pinion 55 which in drives gear 56 on the volume control shaft 57. This drive for one direction of rotation of the knob 31 is illustrated by arrows in Fig. 6. The first few degrees of rotation of the knob 31 in the proper direction, results in the closure of starting switch 3 and continued rotation of the knob 31 thereafter in the same direction will serve to operate the volume control unit 2, thereby increasing the output volume of the set. If the knob 31 is now turned in the reverse direction while still holding the same in its outer or forward position, (see Fig. 6) the volume will be reduced until finally the switch 3 will open, thereby stopping the operation of the set. Upon releasing knob 31, the tension of spring 30 will serve to move the same to its retracted position shown in Fig. 1, thereby permitting spring 50 to turn pawl 44 so as to release ratchet wheel 39 and lock ratchet wheel 43. 50

To tune the set at the set itself or by local control, the operator merely turns the knob 31, thereby turning the arm 37 of the second differential gear set in the same direction as that of knob 31 but at half the speed of this knob. Since bevel gear 35 is locked against rotation, the arm 37, acting through pinions 38 serves to turn bevel gear 36 in the same direction as knob 31 and at the same speed as this knob. The turning 55

70

75

75

of gear 36 causes pulley 40 to turn thereby driving cable 41 and turning the tuning dial 4 as desired.

To provide for the remote control of the radio set, a remote control unit or controller designated as a whole by the reference numeral 69 is employed. This remote control unit or controller consists of a casing 60 (see especially Figs. 3 to 5) illustrated as having an insulating base 61 and a top 62. A remote control knob 63 is positioned above the top 62 of the casing, and this knob is secured to the upper end of a vertical shaft 64. Shaft 64 has its upper portion rotatably and slidably mounted in a bearing provided in the top 62 and its lower portion similarly mounted in a bearing provided in a supporting bracket 65 that is attached by tubular spacing members 66 and screws to the top 62 of the casing.

A pinion 69 is fixed upon shaft 64 immediately below the top 62 of the casing. Pinion 69 is adapted to mesh with a gear 70 that is secured as by a pin 71 to a vertical tubular shaft 72 that is turnably mounted upon a vertical shaft 80 and is also journaled in a bearing provided in the top 62. The lower portion of shaft 80 is journaled in a bearing provided in the base 61 of the casing 60. The upper portion of shaft 72 projects above the top 62 and has a tuning dial 73 secured thereto. Tuning dial 73 has graduations 74 thereon that preferably are similar to and conform with the graduations 75 on the tuning dial 4 on the radio set.

Vertical shaft 64 has another pinion 76 fixed thereon which pinion meshes with a wider idler pinion 77 that in turn meshes with a gear 78 that is fixed upon shaft 80. The lower reduced end of idler pinion 77 is turnably mounted in bracket 65 whereas the upper reduced end of this pinion is turnably mounted in a bracket 79 that is also supported from the top 62 by means of spacing members 66 and suitable screws (see Fig. 5).

The lower end of shaft 64 rests upon the upper spring contact blade 81 of a switch having a lower stationary contact blade 82. The said contact blades being carried by an insulating member 83 that is attached to the side wall of casing 60. Spring contact blade 81 is electrically connected by a lead 84 (see especially Fig. 1) to a current supply lead 85, whereas contact blade 82 is connected by a lead 86 to one side of the coil 49 of electro-magnet 48. The other side of the electro-magnet 48 is connected by a lead 87 to the other current supply lead 88.

A cylindrical brush holder 89, illustrated as of insulating material, is attached to the shaft 71 as by a screw 90. Brush holder 89 carries two oppositely extending electrically conducting brushes 91 and 92 which brushes engage diametrically opposite points of an annular resistor 93. The resistor 93 may be made of suitable conducting and insulating materials held together by a binder such as a phenolic condensation product. The resistor 93 is illustrated as set into an annular recess provided therefor in the base 61. Brush 91 is electrically connected as by a screw 94 to a slip ring 95, whereas brush 92 is electrically connected by a similar screw to a slip ring 96. Slip rings 95 and 96 are engaged respectively by spring pressed contact plungers 97 and 98, the said contact plungers being electrically connected by conducting blades 100 and 101 to leads 102 and 103, respectively, that in turn are supplied with alternating current.

Three binding posts 104, 105 and 106 are arranged around the annular resistor 93, the said

binding posts being spaced 120° with respect to one another. These binding posts are electrically connected by clips 107 to points on the resistor 93 that are spaced 120° apart. Binding posts 104, 105 and 106 are connected by leads 108, 109 and 110 to spring pressed contact plungers 111, 112 and 113 (see Fig. 2), that are similar to contact plungers 97 and 98 and are mounted on an insulating base 114 of a casing 115 that is supported as by bracket 116 upon the frame 102 within the radio set. Contact plungers 111, 112 and 113 engage slip rings 117, 118 and 119, respectively, that are carried by a brush holder 124. Brush holder 124 is illustrated as fixed upon the hub of a gear 125 that is rotatably supported upon the motor shaft 11. Gear 125 meshes with a driving pinion 126 that is fixed upon worm shaft 16. Slip rings 117, 118 and 119 are electrically connected to brushes 120, 121 and 122, respectively, which brushes are carried by the brush holder 124 and engage an annular resistor 127 that is identical with resistor 93 in the controller 59. The brushes 120, 121 and 122 engage the resistor 127 at points spaced 120° with respect to one another as especially shown in the wiring diagram of Fig. 7.

The resistor 127 is tapped at four points spaced 90° with respect to one another as by binding posts 128 and taps 129. Two opposite taps are connected by leads 130 and 130' to the ends of a coil 131 of a relay 132. The two remaining opposite taps are connected by leads 133 and 133' to the ends of a coil 134 of relay 132. Relay 132 has a pivoted armature 135 that is adapted to bridge either of two pairs of contacts 136 or 137. Contacts 136 are connected in series with shading coils 9 and 9' of motor 6 by leads 138, 139 and 140. Contacts 137 are connected in series with shading coils 10 and 10' by leads 141, 142 and 143.

In use, assume that it is desired to start and operate the radio set from a desired remote point of control, i. e. from the controller or remote control unit 59. To accomplish this, the remote control knob 63 is first pressed downwardly somewhat against the upward tension of spring contact blade 81. Shaft 64 is thus moved downwardly, thereby also moving pinions 69 and 76 downwardly. Pinion 69 is thus caused to move out of mesh with gear 70 but pinion 76 remains in mesh with idler pinion 77 owing to the relatively large width of this latter pinion. The downward movement of shaft 64 causes contact blade 81 to engage contact blade 82, thereby completing a circuit by way of leads 84 and 86 (see Fig. 1) for the coil 49 of electro-magnet 48. This electro-magnet thereupon attracts arm 47 of pawl 44 causing this pawl to lock ratchet wheel 39 against rotation.

If the remote control knob 63 is now turned while still held in its depressed position, the pinion 76 acting through idler 77 will drive gear 78, thereby turning shaft 80 carrying the brush holder 89. Shaft 80 turns within tubular shaft 72 so that the tuning dial 73 is not turned at this time. The turning of the brush holder 89 causes brushes 91 and 92 to shift their positions upon the annular resistor 93.

Since A. C. line voltage is supplied by leads 102 and 103, through conducting blades 100 and 101, contact plungers 97 and 98, and slip rings 95 and 96 to brushes 91 and 92, it is evident that the distribution of potential will be uniform throughout the two halves of the resistor 93 at each side of the diametrically disposed brushes 75.

91 and 92. Thus, by referring to the wiring diagram of Fig. 7, with the brushes 91 and 92 in the positions shown, it will be noted that the potential difference between binding posts 106 and 104 will equal the potential difference between posts 106 and 105, such potential difference being equal to two-thirds of the line voltage.

Leads 108, 109 and 110 serve to establish the same potentials at the points of contact of brushes 120, 121 and 122 upon resistor 127 that exist at the binding posts 104, 105 and 106 of resistor 93. Since leads 130, 130' and 133, 133' leading to the relay coils 131 and 134 are tapped upon resistor 127 at four points spaced 90° apart from each other, it is evident that coils 131 and 134 will carry equal currents only if the distribution of potential around the resistor 127 is symmetrical or balanced with respect to a diametric line, as line A—A extending at 45° with respect to the four taps. The potential or voltage distribution on the resistor 127 is governed by the position of the brushes 91 and 92 of the remote control unit and hence as these brushes are shifted by the turning of the depressed remote control knob 63, the balanced line of voltage distribution A—A moves in synchronism with the movement of brushes 91, 92 causing one of the relay coils 131 or 134 to be subjected to a higher voltage than the other, depending upon the direction in which knob 63 is turned. The relay coil receiving the higher voltage, for example coil 131, will then tilt relay armature 135 as shown in Fig. 7, thereby bridging contacts 137 and short circuiting shading coils 10 and 10'. The short circuiting of coils 10 and 10' will start the motor 6 running in one direction. If coils 9 and 9' had been short circuited the motor 6 would run in the reverse direction as is well known to those skilled in the art.

Returning now to the starting of the radio set from the controller 59, the knob 63 has been depressed energizing electro-magnet 48 resulting in the locking of ratchet wheel 39. The knob 63 is then turned in the proper direction, causing turning movement of brushes 91 and 92 resulting in the operation of relay 132 and the starting of motor 6. Motor 6 then runs in the proper direction causing pinion 14 to drive gear 15 which causes worm 17 to drive worm wheel 18, and hence the bevel gear 19 of the first differential gear set is rotated. The frictional resistance of spring 30 on coupling disc 26 serves to hold bevel gear 20 stationary, so that bevel gear 19, acting through pinions 23, serves to revolve arm 22 and shaft 33. Shaft 33 revolves arm 31 of the second differential gear set and since bevel gear 36 of this set is fixed, the bevel gear 35 is rotated thereby acting through gears 55 and 56 to turn shaft 57 of volume contact unit 2. The first few degrees turning of shaft 57 serves to operate switch 3 to closed position, thereby starting the radio set. Any continued movement of shaft 57 thereafter results in varying the output volume of the set.

The turning of the worm shaft 16 causes pinion 126 thereon to drive gear 125 which in turn revolves brush holder 124 carrying brushes 120, 121 and 122. Thus, these brushes 120, 121 and 122 are caused to follow up the motion of brushes 91 and 92 of the remote control unit, thereby restoring the electrical balance of the resistor 127. Thus, in effect when the depressed remote control knob 63 is turned, causing brushes 91 and 92 to turn through a definite angle the motor 6 runs until brushes 120, 121 and 122 turn through a similar angle, whereupon the voltages impressed on relay

coils 131 and 134 again become equal resulting in the opening operation of relay 132 and the stopping of the motor. Thus, the volume of the set may be increased or decreased at will by turning the depressed remote control knob 63 in one direction or the other.

If now it is desired to tune the set, the slight downward pressure upon knob 63 is released permitting spring contact blade 31 to raise shaft 64 to its position shown in Fig. 4, in which position the circuit for electro-magnet 48 is broken and pawl 44 is turned by spring 50 so as to lock ratchet wheel 43. The turning of knob 63 now serves to tune the radio set. This will be apparent when it is noted that as knob 63 is turned, shaft 64 acting through gears 76, 77 and 78 serves to turn shaft 80 and brushes 91 and 92. As before, this shifts the balanced line of potential on resistor 127 resulting in the strengthening of the flux passing through one of the relay coils 131 and 134 causing motor 6 to start rotating in the direction conforming to the direction of turning of knob 63. Motor 6 acts through gears 14, 15, 17 and 18 to revolve arm 22 of the first differential gear set (gear 20 is held stationary by frictional resistance of spring 30) in the desired direction, thereby rotating arm 37 of the second differential gear set. Since bevel gear 35 is locked, bevel gear 36 is turned, thereby turning pulley 49 and causing cable 41 to turn the tuning dial 4 as desired. As before, the brushes 120, 121 and 122 follow up the motion of the brushes 91 and 92 and turn through the same angle as the latter brushes.

The turning of knob 63 also caused pinion 69 to turn gear 70, thereby turning shaft 72 and tuning dial 73 of the remote control unit. Preferably, the speed ratio of tuning dial 73 to that of brushes 91 and 92 is the same as the speed ratio of the set tuning dial 4 to that of the brushes 120, 121 and 122, thereby causing the movements of the dials 40 73 and 4 to be synchronized and enabling similar and easy tuning from either the local or remote control knobs 31 and 63.

The manner of electrically interconnecting the resistors 93 and 127 shown in Fig. 7 is but one of many ways of accomplishing this result and it is not intended to limit this invention to the particular manner shown in the figure. For example, in Fig. 8 there is illustrated another way of interconnecting the resistors. In Fig. 8 the resistors 50 are numbered 93' and 127' and each has but one tap. A lead 145 extends between the resistor taps 155 and 156 and has the coil 146 of a relay 147 included therein. The line A. C. voltage from leads 148 and 149 is introduced into both resistor 55 units by means of slip rings and diametrically opposite brushes 150, 151, 152 and 153. When the angular position of the diametrically arranged brushes 150, 151 with respect to tap 155 is the same as the angular position of the diametrically arranged brushes 152, 153 with respect to tap 156, then the potential difference between taps 155 and 156 is zero and the armature 157 of relay 147 aligns itself with the poles of core 158 as shown in dot and dash lines in Fig. 8. In this neutral 65 position of the armature 157 the motor shading coils connected to leads 133, 140' and 141', 143' are all open circuited so that the motor does not run. If now the remote control knob is turned, causing brushes 150 and 151 to turn clockwise, for 70 example, from the dotted line to the full line position in Fig. 8, then a potential difference is created between taps 155 and 156 and the current passing through coil 146 as a result would cause the armature 157 of field coil 159 to tend to move 75

out of the field in a certain direction depending upon the phase of the voltage introduced into coil 146, resulting in the bridging of the pair of contacts 136', thereby starting the motor in such a direction as to move brushes 152 and 153 into a position corresponding to brushes 150 and 151, i.e. a position where the neutral no-voltage balance is restored.

When using this arrangement, wherein line 10 A. C. is introduced into both resistors 93' and 127' the current supply for the whole radio set may be supplied from the remote control unit through the leads 148, 149, in which event a plug connection could be attached to the remote control unit 15 and the on-and-off position of the radio set could be controlled by insertion or removal of the plug into or from a wall socket convenient to the operator.

It will be noted that the local control knob 31 20 is operated entirely independently of the remote control knob 63 and vice versa. Either of these knobs may be used at any time or even simultaneously with the other without interfering with one another. The use of but a single knob for controlling all operations of the set greatly simplifies the control thereof and renders the operation of the set a relatively easy matter.

Owing to the use of the tuning dial 73 at the remote control unit, which tuning dial is synchronized 30 with the tuning dial 4 at the radio set, it is very easy for the operator at the remote point of control to predict the future position of the tuning element of the set. Thus, if a station tunes at 60, all the operator need do is to turn the remote control knob 63 so as to bring the 60th graduation on dial 73 opposite the indicating mark 160 on the top 62 of the casing. He then knows that the set tuning dial 4 will be moved to the same position, thereby bringing in the 40 station.

Owing to the compactness and simplicity of the device of the present invention, the same takes up but little space and can be readily installed in connection with radio sets, the remote control unit 59 being exceedingly compact and occupying a minimum of space at the operator's position. Inasmuch as there are no rapidly moving parts in the device and as these parts may be sturdily constructed, the device has been found to be very 50 reliable in use and is substantially fool proof. It will be noted that ready control of the volume of the set may be had by use of the remote control knob 63 without in any way upsetting the synchronized relation of tuning dial 73 with the set tuning dial 4. It will be noted that the first 55 differential gear set 19, 20, 22 serves to permit either hand or power operation of the radio set, whereas the second differential gear set 35, 36, 37 serves to permit either the tuning or the volume 60 to be controlled as well as the starting and stopping of the set.

It will be noted that remote control dial 73 together with the brushes 91 and 92 may be turned through as much as 360° or even more, if desired, 65 and the tuning dial 4 of the set will be caused to follow suit. Although the novel control system of this invention has been shown and described in connection with the operation of the volume control element and tuning element of a radio set, it is to be understood that the same is equally applicable to other uses where two elements are to be selectively operated.

Although the novel control device of this invention has been described as adapted to operate 70 two independently operable elements or means,

i. e. the volume control and tuning control of a radio set, it is to be understood that the same is equally applicable for operating more than two elements or independent means. Thus, in Figs. 9 and 10, the device is shown as adapted for operating three independently operable elements, namely, the volume control, tuning control and tone control of a radio set, although it is to be understood that other plural means unrelated to radio receiving could be so operated.

In these figures, the local control knob 31' is shown fixed upon the hub 162 of the coupling disc 26', the said hub 162 being journaled in the front panel 1'. Disc 26' is adapted to drive yoke member 24' having the pins 25'. Yoke member 24', 15 as described in connection with the preceding figures, is fixed upon hub 21' of the first differential gear set consisting of bevel gears 19' and 20' and pinions 23' carried by arm 22' fixed on shaft 33'. Worm 17', driven from the reversible 20 motor in the same manner as previously described, drives the worm wheel 18' that is fixed on gear 19'.

The forward end of shaft 33' is journaled in the hub 162 and a compression spring 30' surrounds 25 shaft 33' for urging coupling members 24' and 26' apart. A latch bar 163 is pressed by a spring 167 against the periphery of coupling disc 26'. Latch bar 163 has three notches 164, 165 and 166 thereon for engaging the periphery of coupling 30 disc 26' to hold this disc against undesired longitudinal movement. Pressure upon knob 31' will serve to move coupling disc 26' from its engagement with notch 166 as shown in Fig. 9 and into engagement with notches 165 and 164, successively, either of these notches serving to hold disc 26' against the pressure of spring 30'.

Arm 37' of the second differential gear set is fixed upon shaft 33' and carries pinions 38' that mesh with gears 35' and 36'. The hub 34' of gear 35' carries a pinion 55' that meshes with gear 56' fixed on the operating shaft 57' of the volume control unit 2' having the starting switch 3' incorporated therein. A ratchet wheel 43' is fixed 40 on bevel gear 35' and is normally held stationary 45 by a double acting pawl 168 (see especially Fig. 10) pivoted at 169 on frame 12'. A tension spring 170 urges pawl 168 against ratchet wheel 43'. An electro-magnet 171, when energized, is adapted 50 to move pawl 168 out of engagement with ratchet wheel 43' and into engagement with ratchet wheel 172 that is fixed on a bevel gear 173 of a third differential gear set. Also, a cam 174, carried on the rear end of a rod 175, when moved rearwardly, 55 actuates an arm 176 on pawl 168 and causes this pawl to disengage ratchet wheel 43' and engage ratchet wheel 172. The forward end of rod 175 terminates adjacent coupling disc 26' to be actuated 60 by the latter.

Bevel gear 36' instead of having a ratchet wheel thereon as in Figs. 1 to 8, has a gear 177 fixed thereon that meshes with a gear 178 fixed on a shaft 179. Shaft 179 has the arm 180 of the third differential gear set fixed thereon. Arm 180 carries pinions 181 that mesh with bevel 65 gears 173 and 182. Gear 182 has a ratchet wheel 183 fixed thereon and also provides a pulley for a transmission belt 41' that is connected to the tuning dial (not shown) in the same manner as belt 41 previously described. Gear 173 is connected through gears 184 and 185 to the control 70 shaft 186 of the tone control unit 187 of the radio set.

A double acting pawl 188, pivoted at 189, is 75 normally caused to lock ratchet wheel 172 against

rotation by the action of a tension spring 190. A link 191 has its rear end connected to pawl 188 and its forward end connected to a lever 192 pivoted at 193, the said lever having its upper end touching the disc 26' when this disc is in the position shown in Fig. 9. Pushing knob 31' rearwardly so that disc 26' enters notch 165 will cause lever 192 to turn, thereby moving link 191 forwardly and causing pawl 188 to engage and lock ratchet wheel 183. This same result may be obtained for energizing an electromagnet 194 which will then attract an armature 195' provided on pawl 188.

It will be noted that the local control knob 31' is adapted to have three longitudinal positions determined by the notches 164, 165 and 166 instead of the two longitudinal positions provided for the knob 31 in Fig. 1. If knob 31' is turned while in its position shown in Fig. 9, i. e. with disc 26' engaging notch 166, gear 20' will turn, thereby turning arm 22' which in turn will turn shaft 33'. Shaft 33' will turn arm 31' of the second differential gear set, and since ratchet 43' is locked, gears 36' and 177 turn thereby causing shaft 179 to turn arm 180 of the third differential gear set. Since ratchet 172 is locked by pawl 188, gear 182 is revolved, thereby driving belt 41' and hence operating the radio tuning dial.

If knob 31' is pushed into its intermediate position, i. e. so that disc 26' engages notch 165, the lever 192 and link 191 will be actuated to cause pawl 188 to lock ratchet wheel 183. If the knob 31' is now turned, the several differential gear sets will operate to cause gear 173 of the third differential gear set to revolve, thereby operating the tone control 187.

If knob 31' is pushed into its innermost position, i. e. so that disc 26' engages notch 164, the rod 175 will be pushed rearwardly by disc 26', thereby causing cam 174 to raise arm 176 and cause pawl 168 to disengage ratchet 43' and engage ratchet 172. A coupling 208 in link 191 permits this link to elongate slightly at this time. If knob 31' is now turned, the first two differential gear sets will operate to effect the turning of the volume control shaft 57'. At this time both gears 173 and 182 of the third differential gear set are locked.

The remote control knob 63' also has three longitudinal positions, determined by three notches 195, 196 and 197 in vertical shaft 64', which notches cooperate with a spring pressed plunger 207. The gearing and associated structure in remote control unit 59' are similar to that in unit 59 and are similarly numbered. Three contact blades 198, 199 and 200 are employed in control unit 59'. Blade 199 is connected by lead 201 to one side of an A. C. source. Blade 198 is connected by lead 202 to electro-magnet 194 and from thence by lead 204 to the other side of the A. C. source. Blade 200 is connected by lead 203 to electro-magnet 171 and from thence by lead 205 to the other side of the A. C. source.

If knob 63' is turned while in its highest position shown in Fig. 9, pinion 69 will turn gear 70, thereby causing the starting of the reversible motor (not shown) just as when knob 63 of controller 59 was turned when in its upper position. The operation of the motor will cause worm 17' to act through the three differential gear sets to effect operation of the radio tuning dial and the remote tuning dial 13 will also turn.

If knob 63' is pressed downwardly to its intermediate position with plunger 207 engaging notch

196, then contact blade 198 will be caused to engage contact blade 199 resulting in the energizing of electro-magnet 194 so that ratchet 183 is locked by pawl 188. The turning of knob 31' will now cause operation of the tone control unit 5 187 as will be apparent.

If knob 63' is pressed downwardly to its lowest position with plunger 207 engaging notch 197, then contact blades 198, 199 and 200 are all engaged resulting in the energization of electro-magnets 194 and 171 so that ratchets 183 and 172 are locked and ratchet 43' is free. The turning of knob 31' will now cause operation of the volume control 2' and switch 3'.

Thus, by using three differential gear sets and 15 three longitudinal positions of the local and remote control knob 31' and 63', three independent elements or means may be controlled. By adding additional differential gear sets and correspondingly increasing the number of longitudinal positions of the local and remote control knobs, four, 20 five or more elements or means may be controlled independently of each other.

As many changes could be made in the above construction and many apparently widely different embodiments of this invention could be made without departing from the scope thereof, as defined by the following claims, it is intended that all matter contained in the above description or shown in the accompanying drawings shall be interpreted as illustrative and not in a limiting sense. 30

I claim:

1. In a control device of the character described arranged to selectively operate either one or the other of two controlled members, reversible motor means, differential gearing driven by said motor means, said differential gearing being connected in driving relation to the two controlled members, means controlled from a desired remote point for presetting said differential gearing, whereby said gearing is stopped from driving one of said controlled members, a relay for controlling the operation of said motor means, a local resistor element electrically connected to said relay 40 for controlling the operation of the latter, a remote resistor element electrically connected to said local resistor element, manually operable brush means movable over said remote resistor element for supplying electrical energy thereto and for causing the operation of said relay to effect the starting of said motor means in the proper direction, additional brush means movable over said local resistor element and driven from said motor means for repeating the motion of 50 said manually operable brush means, whereupon said relay is again operated to stop said motor means, whereby the movement of the selected controlled member is proportional to that of said manually operated brushes. 60

2. In a control device of the character described arranged to selectively operate either one or the other of two controlled members, reversible motor means, differential gearing driven by said motor means, said differential gearing being connected in driving relation to the two controlled members, means controlled from a desired remote point for presetting said differential gearing, whereby said gearing is stopped from driving one of said controlled members, a relay for controlling the operation of said motor means, a local resistor element electrically connected to said relay for controlling the operation of the latter, a remote resistor element electrically connected to said local resistor element, manually operable brush 65 means movable over said remote resistor element for supplying electrical energy thereto and for causing the operation of said relay to effect the starting of said motor means in the proper direction, additional brush means movable over said local resistor element and driven from said motor means for repeating the motion of 70 said manually operable brush means, whereupon said relay is again operated to stop said motor means, whereby the movement of the selected controlled member is proportional to that of said manually operated brushes. 75

- means movable over said remote resistor element for supplying electrical energy thereto and for causing the operation of said relay to effect the starting of said motor means in the proper direction, additional brush means movable over said local resistor element and driven from said motor means for repeating the motion of said manually operable brush means, whereupon said relay is again operated to stop said motor means, whereby the movement of the selected controlled member is proportional to that of said manually operated brushes, and manually operable means positioned adjacent said two controlled members for enabling local operation of said controlled members, said manually operable means being mechanically connected to said differential gearing and to said presetting means.
3. A control device of the character described adapted to selectively operate either one or the other of two controlled members, said device comprising, reversible motor means, a relay for controlling the operation of said motor means, a resistor element electrically connected to said relay for controlling the operation of the latter, a second resistor element located at a remote point of control and electrically connected to said first resistor element, manually operable brush means movable over said second resistor element for supplying electrical energy thereto, additional brush means movable over said first resistor element and driven from said motor means for repeating the motion of said manually operable brush means, differential gearing driven from said motor means and connected in driving relation to said two controlled members, and means operable from said remote point of control for presetting said differential gearing, whereby the desired controlled member is operated upon the starting of said motor means.
4. A control device of the character described adapted to selectively operate either one or the other of two controlled members, said device comprising, reversible motor means, a relay for controlling the operation of said motor means, a resistor element electrically connected to said relay for controlling the operation of the latter, a second resistor element located at a remote point of control and electrically connected to said first resistor element, manually operable brush means movable over said second resistor element for supplying electrical energy thereto, additional brush means movable over said first resistor element and driven from said motor means for repeating the motion of said manually operable brush means, differential gearing having a piston carrying arm driven from said motor means and opposed gears selectively driven from said arm, and mechanism operable from said remote point of control for holding either one or the other of said opposed gears at will, whereby said motor means is caused to operate the selected controlled member.
5. A control device of the character described adapted to selectively operate either one or the other of two controlled members, said device comprising, reversible motor means, a relay for controlling the operation of said motor means, a resistor element electrically connected to said relay for controlling the operation of the latter, a second resistor element located at a remote point of control and electrically connected to said first resistor element, manually operable brush means movable over said second resistor element for supplying electrical energy thereto, additional brush means movable over said first resistor element and driven from said motor means for repeating
- the motion of said manually operable brush means, differential gearing having a pinion carrying arm driven from said motor means and opposed gears selectively driven from said arm, mechanism operable from said remote point of control for holding either one or the other of said opposed gears at will, whereby said motor means is caused to operate the selected controlled member, a local control knob, and additional differential gearing connected to said first named differential gearing and to said local control knob for enabling local selective operation of said controlled members.
6. In a control device of the character described for selectively operating either one or the other of two controlled members, in combination, a differential gear set having an arm carrying a pinion and a pair of opposed gears meshing with said pinion, reversible motor means connected in driving relation to one of said gears, a local control knob connected in driving relation to the other of said gears, a second differential gear set having an arm carrying a pinion and a pair of opposed gears meshing with said pinion, the arm of said second differential gear set being connected to the arm of said first differential gear set to be driven by the latter, one of the opposed gears of said second differential gear set being connected in driving relation to one of the controlled members, and the other of the opposed gears of said differential gear set being connected in driving relation to the other of the controlled members, and means operable at will for holding either one or the other of the opposed gears of said second differential gear set, whereby the other of said gears is caused to drive the controlled member that it is desired to operate.
7. In a control device of the character described for selectively operating either one or the other of two controlled members, in combination, a differential gear set having an arm carrying a pinion and a pair of opposed gears meshing with said pinion, reversible motor means connected in driving relation to one of said gears, a local control knob connected in driving relation to the other of said gears, a second differential gear set having an arm carrying a pinion and a pair of opposed gears meshing with said pinion, the arm of said second differential gear set being connected to the arm of said first differential gear set to be driven by the latter, one of the opposed gears of said second differential gear set being connected in driving relation to one of the controlled members, and the other of the opposed gears of said differential gear set being connected in driving relation to the other of the controlled members, means operable at will for holding either one or the other of the opposed gears of said second differential gear set, whereby the other of said gears is caused to drive the controlled member that it is desired to operate, and means for controlling the operation of said reversible motor means from a remote point, said control means comprising, a relay and a pair of resistors, one of said resistors being located adjacent said motor means and the second at the remote point, manually operable potential supplying brushes movable over said second resistor, additional brushes movable over said first resistor, said additional brushes being driven from said motor means for following up the motion of said manually operated brushes, said relay and said pair of resistors being electrically interconnected, whereby a shifting of potentials on said second resistor due to the

- shifting of said manually operable brushes there-over, will cause a corresponding shifting of potentials on said first resistor, causing the operation of said relay and the starting of said motor means in the proper direction to shift said additional brushes into synchronism with said manually operable brushes.
8. In a control device of the character described adapted to selectively operate either a tuning control element or a volume control element of a radio set from either local or remote points, in combination, a motor, gearing including differential mechanism connecting said motor to the tuning control element and the volume control element, said gearing including means for presetting said differential mechanism, whereby operation of said gearing will drive either the tuning control element or the volume control element as desired, a controller located at a desired remote point, said controller having a resistor, electric current supply brushes movable over said resistor and a remote control knob for manually operating said brushes, a second resistor located adjacent said motor, brushes driven by said motor and movable over said second resistor, a relay for controlling the operation of said motor, leads interconnecting said resistors and said relay whereby the turning of said remote control knob causes said relay to operate said motor until said motor driven brushes have moved through the same angular distance as said manually operated brushes, said motor simultaneously operating said gearing to drive the desired control element of the radio set, whereby the movement of said control element is proportional to that of said remote control knob, and a local control knob at the set mechanically connected to operate through said differential mechanism to effect selective operation of said set control elements.
9. In a control device of the character described adapted to selectively operate either a tuning control element or a volume control element of a radio set from either local or remote points, in combination, a motor, gearing including differential mechanism connecting said motor to the tuning control element and the volume control element, said gearing including means for presetting said differential mechanism, whereby operation of said gearing will drive either the tuning control element or the volume control element as desired, a controller located at a desired remote point, said controller having a resistor, electric current supply brushes movable over said resistor and a remote control knob for manually operating said brushes, switch means operable by said remote control knob for controlling the action of said presetting means, a second resistor located adjacent said motor, brushes driven by said motor and movable over said second resistor, a relay for controlling the operation of said motor, leads interconnecting said resistors and said relay whereby the turning of said remote control knob causes said relay to operate said motor until said motor driven brushes have moved through the same angular distance as said manually operated brushes, said motor simultaneously operating said gearing to drive the desired control element of the radio set, whereby the movement of said control element is proportional to that of said remote control knob, a local control knob at the set mechanically connected to operate through said differential mechanism to effect selective operation of said set control elements, and mechanism connecting said local control knob to said presetting means for enabling local operation of the latter.
10. In a control device of the character described, a remote control unit comprising, a casing, an annular resistor mounted within said casing, a shaft extending axially of said resistor, a brush holder fixed on said shaft and having a brush contacting with said resistor, a remote control knob positioned exteriorly of said casing and having a shaft extending into the latter, gearing within said casing connecting said control knob shaft within said casing to said brush holder shaft, whereby the turning of said knob will effect the turning of said brush, switch contacts within said casing, said control knob shaft being movable by pressure on said control knob to effect the engagement of said switch contacts, a tuning indicator turnably mounted on said brush holder shaft, and additional gearing for connecting said tuning indicator to said control knob shaft to be driven from the latter, said gearing being disconnected upon movement of said control knob shaft to effect the engagement of said switch contacts.
11. In a control device of the character described adapted to selectively operate two independently turnable operating elements, a turnable hand actuated control knob, differential gear mechanism interconnecting said control knob with said operating elements, said differential gear mechanism comprising a pair of bevel gears connected respectively in driving relation to said respective operating elements, a pinion meshing with said pair of bevel gears, a rotatable arm carrying said pinion, shafting supporting said arm and connected in driven relation from said control knob, and means connected to said control knob and operated by axial movement thereof for selectively holding either of said bevel gears against rotation, whereby said control knob may be moved axially to pre-set said differential gear mechanism to thereby determine the particular operating element to be turned, the turning of said control knob thereafter serving to manually actuate said differential gear mechanism and cause operation of the selected operating element.
12. In a control device of the character described adapted to selectively operate two independently adjustable operating elements from either local or remote points of control, hand actuated control knobs positioned at the local and remote points of control, said knobs being mounted for axial and turning movement, operating means interconnecting said control knobs with said operating elements, said operating means comprising mechanism including differential gearing connecting said local control knob to said operating elements and electrical repeating mechanism interconnecting said remote control knob to said differential gearing, said operating means including means connected with said local and remote control knobs so that said control knobs may be moved axially within limits and turned at the limits of such axial movement, the turning of said control knobs when at one end of their respective axial movements serving to cause operation of one of said operating elements, while the turning of said control knobs while at the other end of their respective axial movements serving to cause operation of the other of said operating elements.
13. In a control device of the character described adapted to selectively operate two independently adjustable operating elements from

- either local or remote points of control, hand actuated control knobs positioned at the local and remote points of control, said knobs being mounted for axial and turning movement operating means interconnecting said control knobs with said operating elements, said operating means comprising mechanism including differential gearing connecting said local control knob to said operating elements and electrical repeating mechanism interconnecting said remote control knob to said differential gearing, said operating means including means connected with said local and remote control knobs so that said control knobs may be moved axially within limits and turned at differing points of such axial movement, the turning of said control knobs when at one point of their respective axial movements serving to cause operation of one of said operating elements, while the turning of said control knobs while at another point of their respective axial movements serving to cause operation of another of said operating elements, said control knobs having individual indicating means associated therewith for visually indicating the extent of operation of one of said operating elements.
14. A control device of the character described arranged for operating the tuning and volume control elements of a radio set as well as the starting switch thereof, said control device comprising single local and remote manually operated control knobs for controlling all operations of the set, mechanism connecting said local control knob to the tuning and volume control elements of the set and to the starting switch thereof, said mechanism including means connected with said local control knob whereby said local control knob may be moved axially as well as rotated, said local control knob when rotated while at one end of its axial movement serving to cause operation of the starting switch and the volume control element and when rotated while at the other end of its axial movement serving to cause operation of the tuning control element, additional mechanism cooperating with said first named mechanism, said additional mechanism including a motor and relay means for controlling said motor, said relay means being arranged to be operated from said remote control knob, means connected to said remote control knob whereby said remote control knob may be manipulated in a manner similar to said local control knob to control all operations of the set, and tuning indicating means associated with said remote control knob for visually indicating the operation of the set tuning element.
15. In a control device of the character described adapted to selectively operate independently adjustable operating members, a hand actuated control knob mounted for axial and turning movement, mechanism including differential gearing interconnecting said control knob with said operating members, said mechanism including means connected with said control knob whereby said control knob may be moved axially to any selected one of a plurality of operative positions as well as turned, the turning of said control knob, when positioned at any selected one of its respective axial positions, serving to cause independent operation of a respective one of said operating members.
16. In a control device of the character described adapted to selectively operate a plurality of independently adjustable operating members from either local or remote points of control, hand actuated control knobs positioned at the local and remote points of control, said knobs being mounted for axial and turning movement, operating means interconnecting said control knobs with said operating members, said operating means comprising mechanism including differential gearing connecting said local control knob to said operating elements and electrical repeating mechanism interconnecting said remote control knob to said differential gearing, said operating means including means connected with said local and remote control knobs so that said control knobs may be moved axially to a plurality of positions as well as turned, the turning of either of said control knobs, when positioned at any one of its respective axial positions, serving to cause operation of a respective one of said operating members.

PHILIP L. S. LUM.
